UNITED STATES PATENT OFFICE.

CHARLES E. HEISS, OF CHICAGO, ILLINOIS, ASSIGNOR OF ONE-HALF TO
JAMES N. RAYMOND, OF SAME PLACE.

REEL FOR COILING LEAD PIPE.

SPECIFICATION forming part of Letters Patent No. 334,585, dated January 19, 1886.

Application filed November 11, 1885. Serial No. 182,496. (No model.)

To all whom it may concern:

Be it known that I, CHARLES E. HEISS, a citizen of the United States, residing at Chicago, in the county of Cook and State of Illinois, have invented a certain new and useful Improvement in Reels for Coiling Lead Pipe, &c., which is fully set forth in the following specification, reference being had to the accompanying drawings, in which—

10 Figure 1 represents a plan view of an apparatus embodying my invention; Fig. 2, a sectional view of the same, taken on the line $x-x$ of Fig. 1; Fig. 3, a sectional view taken on the line $y-y$ of Fig. 1; and Fig. 4, a sectional view taken on the line $z-z$ of Fig. 1.

15 Like letters refer to like parts in all the figures of the drawings.

My invention relates to reels for coiling lead pipe and other like articles, its object being to 20 produce a reel upon which the pipe can be formed into a coil cylindrical on its outer surface, and from which the completed coil may be readily removed.

25 I will now proceed to describe a construction in which I have practically carried out my invention in one form, and will then particularly point out in the claims those features which I deem to be new and desire to protect by Letters Patent.

30 In the drawings, A represents a standard, upon which the reels are mounted. In the present instance the reels are shown as mounted in duplicate upon this standard, for the purposes hereinafter stated, being supported upon

35 axles b , projecting from a table, B, mounted upon a pivot, a , on the standard-head. This table is shown, in the present instance, as being circular in form and resting upon the standard-head, with the dimensions of which it corresponds, the axles b projecting therefrom on opposite sides.

40 B' represents a locking pin, which passes through the table B and engages with either one of a pair of recesses, b' , arranged at opposite sides of the standard head, for the purposes hereinafter stated.

45 The construction of the two reels being iden-

tical, although the arrangement is reversed, I will limit myself to the description of one reel, it being understood, of course, that the same 50 description is equally applicable to the other.

C represents a wheel mounted on the axle b , so as to revolve freely thereon, and consisting, in the present instance, of a central hub provided with a series of radial arms, c . These 55 arms are shown, in the present instance, as five in number; but it is obvious, of course, that a greater or less number may be employed, or that a solid disk may be substituted therefor.

60 To the arms c are attached suitable handles or levers, D, by means of which the wheel C and the reel which is mounted thereon may be rotated.

E represents the drum or reel proper, which 65 consists of a cylinder of sheet metal or other flexible material. This reel is supported on the wheel C by means of two fixed supports, F, attached to the wheel C and operating in conjunction with a movable support, G. This 70 latter support is mounted so as to be adjustable toward and from the center of the wheel C, for the purpose of expanding or contracting the drum E. The ends of the sheet of metal composing the said drum are in no way 75 connected to each other, so that the elasticity of the material will permit the drum to expand or contract, according as it is forced outward or allowed to contract inward as the adjustable support G is moved outward or inward.

80 The support G consists of a segmental plate provided with a yoke, g , fitting in a groove, h , in a cylindrical cam, H, which is mounted eccentrically upon a shaft, I, itself mounted in 85 suitable bearings in the wheel C. The shaft I is provided with a crank or handle, I', by means of which it may be rotated to cause the cam H to move the adjustable support G toward or from the center of the reel in an obvious manner. The crank I' is elastic at its outer extremity, having sufficient spring to bear against one of the handles D, and by its friction hold the several parts in the position

shown in the drawings, the cam being upon a center or dead point, so as to prevent the collapse of the drum. A stop, *i*, is attached to the handle *D* to prevent the crank *I'* from being turned too far.

J indicates a counter-weight attached to the wheel *C*, opposite to the support *G* and its operating mechanism, to cause the reel to balance properly.

10 Heretofore in the construction of reels for the purpose of coiling lead pipe as it comes from the press in which it is formed, it has been customary to give to the drum of the reel a frusto-conical shape in order that the pipe may be readily removed from the reel by withdrawing it toward the smaller end. Owing to this construction, the completed coil, when withdrawn from the reel, is not of equal diameter throughout, being smaller at one end, so that 15 in handling the coil by rolling it along the ground, as is customary, it will not roll straight, and therefore requires a considerable amount of labor in transferring it from one point to another. This difficulty is overcome by the 20 use of my improved reel, the operation of which is as follows: The parts being in the position shown in the drawings, the lead pipe, as it comes from the press, is coiled upon one of the reels, which is rotated by means of the handles during 25 this operation. The reel being cylindrical, it is obvious that the coil will also be cylindrical. When the reel is full, it is only necessary to turn the crank *I'* downward, when the reel will collapse and allow the coil of pipe 30 to be removed therefrom without any difficulty. When the reel is constructed in duplicate, as in the construction shown, when one reel is full the locking-pin *B'* may be lifted and the whole upper part of the apparatus removed on the pivot *a* until the other reel is brought into the position originally occupied by the full reel. When this position is reached, the locking-pin will drop into the other recess, and thus determine exactly the proper position 35 for the empty reel. The empty reel may now receive a coil of pipe, while the coil on the other reel is cooling sufficiently to be removed, and thus no time will be lost by stopping the press during the removal of the coil 40 from the reel. It will be seen that in this manner the operation of reeling off the pipe may be made practically continuous, while at the same time the coils of pipe are cylindrical in form and may be readily handled by rolling them along.

55 Another advantage attendant upon my improved reel is as follows: It has been customary to construct reels for coiling lead pipe of wood, since metal reels of similar construction are liable to heat and stick to the pipe, thus hindering its removal. The wooden reels, on the other hand, soon become useless by reason of the charring and burning of the material through the heat of the newly-manufactured pipe.

60 By the use of my improved collapsing reel

I am enabled to obtain the durability of the metallic reel, while at the same time the pipe will not stick, since this latter collapses when it is desired to remove the pipe.

70

I am aware that heretofore reels for coiling wire, rods, &c., have been constructed, the said reels consisting of a series of pivoted arms, the outer ends of which may be drawn toward the center of the reel by suitable mechanism in order to give the reel a conical shape, and thus remove the coil. This is not, however, adapted to the purpose of coiling lead pipe, since it would not produce a cylindrical coil, which is the principal object of my invention. Moreover, in this construction there is no cylindrical drum which, while it is collapsible, retains its cylindrical form, or, in other words, is reduced throughout its entire length to the same extent.

85

I am also aware of the English Patent to Drake, No. 840 of 1883, which shows a grooved roller made in four parts and capable of being made smaller or larger by approaching or separating the sections, and I lay no claim to such a construction.

90

It is obvious that various modifications in the details of construction and arrangement of the parts may be made without departing from the principle of my invention. I therefore do not wish to be understood as limiting myself strictly to the precise details of construction hereinbefore described, and shown in the drawings.

95

Having thus described my invention, what I claim as new, and desire to secure by Letters Patent, is—

100

1. In a reel for coiling lead pipe, a collapsing or contractile drum cylindrical in shape and constructed of an elastic sheet of metal, substantially as and for the purposes specified.

105

2. In a reel for coiling lead pipe, the combination, with the wheel provided with supports, one of which is radially adjustable, of the elastic cylindrical drum mounted on said supports, substantially as and for the purposes specified.

110

3. The combination, with the wheel *C*, having fixed supports *F* and adjustable support *G*, of the elastic sheet-metal cylinder *E*, mounted on said supports, substantially as and for the purposes specified.

115

4. The combination, with the wheel *C*, having fixed supports *F* and movable support *G*, of the cam-cylinder *H*, surrounded by a yoke on the movable support, and the elastic cylinder *E*, substantially as and for the purposes specified.

120

5. The combination, with the movable support *G* and the collapsing cylinder operated thereby, of the cam-cylinder *H*, connected to said support, the shaft *I*, on which said cam is mounted, and the crank-handle *I'*, for operating said shaft, substantially as and for the purposes specified.

125

6. The combination, with the wheel *C*, having fixed and movable supports, and the col-

130

lapsing cylinder mounted thereon, of the shaft I, provided with a cam, H, to operate the movable support, crank-handle I', and stop i, substantially as and for the purposes specified.

5 7. The combination, with a suitable base or support, of a plate pivoted on said support, and two or more reels mounted on said plate, substantially as and for the purposes specified.

8. The combination, with the support A, 15 of the table B, pivoted thereon and provided with axles b, and the reels mounted on said axles, substantially as and for the purposes specified.

9. The combination, with the support A, provided with recesses b', arranged as described, of the table B, pivoted on said support and provided with axles to receive the coiling-reels, and the locking-pin B', substantially as and for the purposes specified.
